TICKET COUNTING MACHINE

Jay Rose, New York, N. Y.

Substituted for abandoned application Serial No.
109,426, November 6, 1936. This application
December 8, 1941, Serial No. 422,063

5 Claims. (Cl. 235—98)

My invention relates to ticket counting machines and has particular reference to machines for registering admission tickets in theaters and similar establishments.

This is a substitute application for my application Serial No. 109,426, filed November 6, 1936.

The object of my invention is to provide a ticket counting machine having a plurality of rolls for propelling tickets or strips of tickets from a receiving chute into a container, operating at the same time a canceling device by the movement of a ticket or strip of tickets between the rolls.

Another object of my invention is to provide a ticket counting machine with a mechanical device operated by moving tickets, the device being adapted to register only normal or full-sized tickets, being inoperative for shortened tickets, for instance, when they are torn in two pieces.

Another object of my invention is to provide a ticket counting machine with a plurality of canceling and propelling rolls for tickets and strips of tickets, the rolls being staggered, one set operating on the edge portions of the tickets, the other on their middle portions. In a preferred arrangement I use middle canceling rolls operating on the middle portions of the tickets, and propelling rolls engaging the edge portions. Mechanical elements, actuating a registering device, are supported between the rolls acting on the edge portions.

Still another object of my invention is to provide a ticket counting machine with a registering attachment adapted to register strip tickets by the holes or openings separating successive tickets.

Still another object of my invention is to provide a ticket registering machine which cancels tickets by cutting off their marginal sides, thereby rendering it impossible to send such canceled tickets again through the machine.

My invention is more fully described in the accompanying specification and drawing, in which:

Fig. 1 is a sectional elevation of my machine;
Fig. 2 is a sectional side view, the left portion of the section being taken on the line 2—2 of Fig. 1;

Fig. 3 is a top plan view partly in section;
Fig. 4 is a detail view showing the portion of the ticket registering mechanism;

Fig. 5 is a detail view of mechanical feelers for the registering mechanism in relation to a strip ticket; and

Fig. 6 is a detail view of cutting rollers.

My ticket counting machine consists of a housing 1 with a fixed cover 2 and a hinged cover 3 on hinges 4 with a lock 5. The hinged cover 5 has apertures or chutes 6 for tickets or ticket strips 7; also pockets 8 for cards 9 indicating the value of tickets for which the particular adjacent chute is being used. A door 10 is provided at the rear side of the housing, the front side having a window 11 for an electric lamp 12. A bracket 13 is supported inside the housing on its side walls by screws 14. The bracket supports ticket canceling units, each unit consisting of side brackets or plates 15 connected together by studs 16 with spacing tubes 17. A guiding block 18 for the tickets is supported between the brackets 15 and consists of two metal plates joined together and forming a channel 20 inside for the tickets. The upper end of the channel 20 is flared out to facilitate the entrance of tickets from the chutes 6.

The brackets 15 have apertures 19 for bearings 21 and 22, the apertures on one side of the unit extending to the edges of the brackets 25 where flanges 23 are formed. Inserts 24 are placed in these slotted apertures for retaining and adjusting the bearings 21. The inserts have flanges 25 secured to the flanges 23 by screws 26, permitting to adjust the position of the inserts and the bearings. Shafts 27 are journaled in the bearings for rolls 28 and 29 spaced so as to engage the edge portions of the tickets passing through the channel 20 in the unit. Slots 30 are provided in the block 13 for the rolls. The upper and the lower pairs of the rolls are connected by pairs of gears 31 and 32 mounted on the ends on the shafts 27, with a driving gear 32'. The latter is in mesh with the gears 31 and 32 on one side of the brackets and is mounted on a shaft 33 journaled in bearings 34 fitted in the brackets 15. The shaft 33 extends across all the units simultaneously driving all the gears. It has a sprocket 37 on the end connected by a chain 38 with a sprocket 39 on the shaft of an electric motor 40 mounted on a bracket 41. Intermediate rolls 42 and 43 of a relatively smaller diameter are mounted on shafts 44 midway between the upper and lower main rolls. The roll 42 has sharp teeth 45 in mesh with corresponding holes in the roll 43 for canceling the tickets by punching holes through their middle portion. The roll 43 has a gear 46 in mesh with the driving gear 32'. The distance between the upper and lower main rolls approximately corresponds to the length of the tickets. Chutes or spouts

47 are supported under the channels 20 for guiding tickets into individual containers 48 for each kind of tickets. The containers can be removed through the rear of the housing by opening the door 10.

Brackets 49 are mounted on one side of the block 18 and are provided with forked ends or clevises for pins 50 on which are pivoted crank levers 51 and 52. The block 18 has slots 53 for the inner ends of the levers. These ends are shaped in the form of sharp feelers reaching into shallow depressions 54 in the opposite side of the block 18, and are adapted to be deflected by the edge of the ticket 7.

The end 70 of the upper feeler is made wide so as to cover holes 55 separating tickets in the strips, so that this feeler becomes deflected only by the edge of a ticket. The lower feeler is sharp-pointed and can fall into the holes 55 as shown in Fig. 4. The outer ends of the levers 51 and 52 are pivotally connected with the ends of a crossbar 56, the middle point of which is pivoted at 57 to one end of a rod 58 sliding in a bearing 35. The other end of the rod has an elongated slot 59 for a pin 60 on a crank lever 61 pivoted at 62. The end of the arm of the lever 61 has a contact point 63 opposite a point 64, forming a switch, connected with the lamp 12. The other arm of the lever 61 is pivotally connected with a rod 65, the other end of which is connected with an operating arm 66 of an ordinary counter 67. The numbers on the face of the counter are exposed through a window in the fixed cover 2 alongside the numbers of an electrically operated counter 68 connected with the ticket issuing machine (not shown) in the box office.

The operation of my apparatus is as follows: A ticket or strip of tickets 7 is deposited for canceling into a corresponding chute 6. The motor 40 running continuously, the upper rolls 28 engage the lower end of the ticket and begin to pull it through the channel 20, the latter being made to suit the particular width and thickness of the tickets. The lower edge of the ticket engages the upper feeler 70 and deflects it as shown in Fig. 4. The other end of the lever 51 moves the upper end of the crossbar 56 through the link 69. The rod 58 is accordingly moved outward. The slot 59 is so arranged that in this position of the rod 58 the rear end of the slot begins to engage the pin 60, but does not yet move the lever 61. The lever 51 remains in this position as long as there is a ticket under the feeler 70, the holes 55 having no effect on the feeler.

The ticket then becomes engaged by the central canceling rolls 42 and 43, which punch a series of holes through the central portion of the ticket, at the same time propelling the ticket further on its way through the slot 20. The intermediate rolls enable, therefore, short tickets or their halves to be pulled through the device, if such shortened tickets happened to be thrown into the chute 6. The lower end of the ticket is then engaged by the lower rolls 29 and almost immediately come in contact with the lower feeler 71, deflecting the lever 52. The latter, through its link 69, pushes the lower end of the crossbar 56, thereby pushing the rod 58. The slotted end of the latter was already engaging the pin 60, so that now it will move the lever 61, closing the switch contacts 63 and 64 for flashing the lamp 12 and pulling the rod 65, thereby turning the arm 66 of the counter 67, which will accordingly

register the ticket. Distance between the feelers 70 and 71 is somewhat smaller than the length of an ordinary ticket, so that only full length tickets can be registered, as both feelers must be deflected in order to actuate the lever 61. Short tickets will be pulled through but will not be registered. Each ticket in a strip will be registered whenever the lower feeler 71 falls into the hole 55 separating the successive tickets.

In a modified arrangement shown in Fig. 6, the canceling is effected by lower rolls 72 and 73. These rolls have sharp-cutting edges spaced preferably nearer the centerline of the tickets than the upper rolls. The lower rolls cut off the side marginal portions of the tickets, and such mutilated narrow tickets cannot be drawn in by the upper rolls if an attempt be made to send such tickets through the canceling device since the width of such tickets is less than the distance between the pair of the upper rolls 28.

It is understood that my ticket counting machine may be further modified without departing from the spirit of the invention, as set forth in the appended claims.

I claim as my invention:

1. A ticket counting machine comprising a guide for tickets, means to pull the tickets through the guide, a counter for the tickets having an operating arm adapted to be reciprocated for operating the counter, two levers rotatively supported at the guide spaced from each other having inner and outer arms, inner arms of the levers forming feelers extending into the guide and adapted to be deflected by the edge of a ticket moving through the guide, the feelers extending at an obtuse angle to the face of the ticket, thereby obtaining a relatively long travel of the point of feeler for a relatively small thickness of the ticket, a cross bar pivotally connected with outer arms of the levers, and operative members extending from a pivot at the middle point of the cross bar to the operating arm, the cross bar arm being adapted to be rotated by the levers about its middle pivot, and being adapted to transmit motion to the arm from the levers only when both feelers are deflected by a ticket of a standard length.

2. A ticket counting machine comprising a guide for tickets, means to pull the tickets, and strips of tickets, through the guide, a counter for the tickets having an operating arm adapted to be reciprocated for operating the counter, two levers rotatively supported at the guide spaced from each other, having inner and outer arms, the inner arms forming feelers extending from the levers into the guide and adapted to be deflected by the edge of a ticket moving through the guide, the feelers extending at an obtuse angle to the face of the ticket, thereby obtaining a relatively long travel of the point of feeler for a relatively small thickness of the ticket, a bar movably supported in the machine, operative connections between one end of the movable bar and the operating arm, a cross bar pivotally connected at the middle to the movable bar, and pivotal connections between the ends of the cross bar and the outer arms of the levers, the cross bar being adapted to be rotated about its pivot when one of the levers is rotated, and being adapted to move the movable bar for operating the counter when both levers are rotated, the feelers being so spaced as to operate the counter only when the ticket of standard length is being pulled through the guide.

3. A ticket counting machine comprising a guide for tickets, means to pull the tickets, and

strips of tickets, through the guide, a counter for the tickets having an operating arm adapted to be reciprocated for operating the counter, two levers rotatively supported at the guide spaced from each other, having inner and outer arms, the inner arms forming feelers extending from the levers into the guide and adapted to be deflected by the edge of a ticket moving through the guide, the feelers extending at an obtuse angle to the face of the ticket, thereby obtaining a relatively long travel of the point of feeler for a relatively small thickness of the ticket, a bar movably supported in the machine, operating connections between one end of the bar and the operating arm, a cross bar pivotally connected at the middle to the movable bar, and pivotal connections between the ends of the cross bar and outer arms of the levers, the cross bar being adapted to be rotated about its pivot when one of the levers is rotated, and being adapted to move the movable bar for operating the counter when both levers are rotated, the feelers being so spaced as to operate the counter only when the ticket of standard length is being pulled through the guide, the lower feeler having a small end for entering holes between consecutive tickets in a strip, the upper feeler having a large end for straddling the hole, thereby preventing registering of a shortened ticket at the end of the strip.

4. A ticket counting machine comprising a guide for tickets, means to pull the tickets, and strips of tickets, through the guide, a counter for the tickets having an operating arm adapted to be reciprocated for operating the counter, two levers rotatively supported at the guide spaced from each other, having inner and outer arms, the inner arms forming feelers extending from the levers into the guide and adapted to be deflected by the edge of a ticket moving through the guide, the feelers extending at an obtuse angle to the face of the ticket, thereby obtaining a relatively long travel of the point of feeler for a relatively small

thickness of the ticket, a bar movably supported in the machine operating connections between one end of the bar and the operating arm, a cross bar pivotally connected at the middle to the movable bar, and pivotal connections between the ends of the cross bar and outer arms of the levers, the cross bar being adapted to be rotated about its pivot when one of the levers is rotated, and being adapted to move the movable bar for operating the counter when both levers are rotated, the feelers being so spaced as to operate the counter only when the ticket of standard length is being pulled through the guide, the lower feeler having a small end for entering holes between consecutive tickets in a strip, the upper feeler having a large end for straddling the hole, thereby preventing registering of a shortened ticket at the end of the strip.

5. A ticket counting machine comprising a guide for tickets, means to pull the tickets, and strips of tickets through the guide, a counter for the tickets having an operating arm adapted to be reciprocated for operating the counter, two levers rotatively supported at the guide spaced from each other, having inner and outer arms, the inner arms forming feelers extending from the levers into the guide and adapted to be deflected by the edge of a ticket moving through the guide, the feelers extending at an obtuse angle to the face of the ticket, thereby obtaining a relatively long travel point of feeler for a relatively small thickness of the ticket, one of the feelers having a small end for entering holes between consecutive tickets in a strip, the other feeler having a wide end passing over the holes, but sliding off the end of the ticket, the feelers being so spaced as to prevent registering a shortened ticket at the end of the strip, and means to transmit mechanical movement from the levers to the counter when both arms are rotated.

JAY ROSE.
